Inventor:
SAMUEL KAUFFMAN,
By John W. Brumley
His Attorney.

UNITED STATES PATENT OFFICE

SAMUEL KAUFFMAN, OF ST. LOUIS, MISSOURI, ASSIGNOR TO AMERICAN METAL PRODUCTS CORPORATION, (DELAWARE), OF ST. LOUIS, MISSOURI

RADIATOR SHIELD

Application filed May 17, 1928. Serial No. 278,448.

This invention pertains to radiator shields, such as are used to cover steam radiators and the like in order to prevent the heated air rising therefrom from coming in contact with the walls thereabove, whereby the soiling of walls and draperies is avoided.

One of the objects of this invention is to provide a radiator shield, which may have a metal or glass top, or the like, and which top is insulated so as to prevent its becoming too hot.

Another object is to provide a shield which will have means for humidifying the air as it is discharged from the radiator.

Another object is to provide a shield with humidifying means so arranged that the heated air will circulate through the humidifier so as to become charged with moisture before passing out into the room.

Further objects will appear from the following description, taken in connection with the accompanying drawing, in which—

Figure 1 is a vertical section of a radiator shield embodying this invention; and

Figure 2 is a similar view of another embodiment of this invention.

Referring to the accompanying drawing, the radiator is shown in dotted lines at 1. The radiator shield is mounted thereon and comprises a pair of end brackets 2, only one of which is shown in each view. Each of these brackets has a vertical portion 3 and a forward extension 4 at its upper end. Mounted on the brackets 2 is an imperforate back plate 5 of sheet metal or other suitable material. The parts are so dimensioned that, when placed in position on the radiator, the brackets 2 will embrace the ends of the radiator while the plate 5 closes the rear portion thereof, so as to prevent any of the heated air from passing rearwardly against the wall 6 before which the radiator stands. The lower end of the plate 5 may have mounted thereon a plate 7 extending rearwardly therefrom at an angle and edged with a strip of felt 8 or similar material, adapted to contact with the wall so as to prevent leakage of air therethrough and to form a dust guide. The shield may be mounted on the radiator by means of bolts 9, or in any other well known manner.

The dust guide 7 prevents the air from passing upwardly behind the radiator and forces it to pass up through the radiator and between the side brackets 2 and thus prevents the dust from striking the wall.

Referring more particularly to the embodiment of Figure 1, there is mounted on the upper extensions 4 of the brackets a plate 10, whose middle portion is depressed so as to provide a water pan 11, which extends along the radiator for such a distance as to provide a sufficient supply of water. The upper portions of the side walls 12 of the pan 11 are perforated, as shown at 13. These perforations are placed high enough to accommodate the desired depth of water in the pan. The forward portion of the plate 10 is curled under so as to provide a dust-catching trough 14. A top member 15 is hinged at 16 to the upper portion of the radiator shield. This member provides a cover adapted to extend over and cover the pan 11 and the entire upper portion of the radiator shield. This cover may be constructed of metal or other material, according to the finish desired.

In the operation of this embodiment of the invention, the air, which is heated by the radiator, passes upwardly, being prevented from coming in contact with the wall by the action of the shield. When the air reaches the upper portion of the shield, it is deflected forwardly and passes through the perforations 13 into the pan 11, passing over the water in said pan. This water is heated by the radiator and its evaporation hastened, so that the air passing thereover will be charged with moisture. The air emerges again through the forward perforations 13 and then passes in a downward curl through the trough 14, where it deposits any dust or suspended matter, and then passes outwardly into the room, as indicated by the arrows in Figure 1. It will be noted that the water pan 11 serves to insulate the top member against the action of the heat generated by the radiator. If this top portion is constructed of a single sheet of metal, it will thus be prevented from becoming uncomfortably warm, so that contact therewith will have no disagreeable effects. Again, if the top is constructed of marble,

glass or similar material, the same is protected against breakage by excessive heating of the top. The top being hinged at 16 makes it convenient to raise this top in order 5 to replenish the water in the pan 11.

In the embodiment of Figure 2, the top plate 10 is substantially flat, but has secured to the under portion thereof a block 17 of insulating material, such as asbestos, or the like. 10 The block 17 may be further supported by one or more brackets or strips 18 secured to the back plate 5. Mounted on the strips 18 are one or more angle iron strips 19 extending along the radiator and arranged to rest 15 upon the top thereof. These strips give additional support to the radiator shield and to any articles which may be placed on the top thereof. In the present case a plain top member 15 of any suitable type may be provided 20 as a finish.

In this embodiment, the insulating block 17 acts to effectively protect the top 15 against any excessive rise of temperature so that the same is kept cool for the reasons already set 25 forth.

It will be noted that this invention accomplishes its objects in providing a radiator shield which not only has its top insulated so as to prevent it from becoming overheated, 30 but which provides humidifying means placed directly in the path of the air circulating through the radiator shield. The humidifying means are so constructed and arranged that the air may circulate through the 35 water pan and over the water contained therein so as to take up immediately the moisture which is evaporated in the pan.

It is obvious that various changes may be made, within the scope of the appended 40 claims, in the details of construction without departing from the spirit of this invention; it is, therefore, to be understood that this invention is not limited to the specific details shown and described.

Having thus described the invention, what 45 is claimed is:

1. A radiator shield comprising, a pair of imperforate end brackets each having a long vertical portion and a short forward horizontal extension, a back plate connecting said vertical portions and arranged to extend upwardly from near the floor back of a radiator, a top plate extending between and connecting 50 said forward extensions to lie over the top of the radiator and terminating at its forward end in a dust-collecting trough, said top plate being formed to provide a water pan over the radiator, and a top overlying said top 55 plate and the pan formed thereby and hinged at its rear to the back plate.

2. In a radiator shield, a top comprising in combination, a plate having its outer edge formed to define a dust trough, an upwardly 60 open pan associated with said plate and ex-

tending therebelow, and a movable cover overlying said plate and closing said pan.

3. A radiator shield, comprising, a pair of imperforate end brackets each having a long vertical portion and a short forward horizontal extension, a back plate connecting said vertical portions and arranged to extend upwardly from near the floor back of a radiator, a top plate extending between and connecting 70 said forward extensions to lie over the top of the radiator and terminating at its forward edge in a dust-collecting trough, a water pan on said top plate having its front and rear walls perforated to provide for passage of air through the pan, and a top overlying said top plate and pan and hinged at its rear to 75 said back plate.

In testimony whereof, I affix my signature this 14th day of March, 1928.

SAMUEL KAUFFMAN.

CERTIFICATE OF CORRECTION.

Patent No. 1,892,954.

January 3, 1933.

SAMUEL KAUFFMAN.

It is hereby certified that the above numbered patent was erroneously issued to "American Metal Products Corporation, (Delaware), of St. Louis, Missouri," whereas said patent should have been issued to "Jack Adler, of St. Louis, Missouri," as assignee by mesne assignments of the entire interest in said invention as shown by the records of assignments in this office; and that the said Letters Patent should be read with this correction therein that the same may conform to the record of the case in the Patent Office.

Signed and sealed this 25th day of April, A. D. 1933.

M. J. Moore,

(Seal)

Acting Commissioner of Patents.
